UNITED STATES PATENT OFFICE

2,099,650

CUSHION TUFTING STRUCTURE

Charles L. Hall, Detroit, Mich., assignor to
United-Carr Fastener Corporation, Cambridge,
Mass., a corporation of Massachusetts

Application March 28, 1934, Serial No. 717,828

6 Claims. (Cl. 155—185)

My invention aims to provide improvements in cushion tufting structures and tufting devices for the same.

In the drawing which illustrates preferred embodiments of my invention:

Figure 1 is a vertical section through a portion of a seat cushion structure showing my improved tufting device;

Fig. 2 is an enlarged section through a portion of the spring covering means, one of my improved tufting clips being shown in side elevation;

Fig. 3 is a side elevation of a tufting clip before attachment;

Fig. 4 is a plan view of the device shown in Fig. 3;

Fig. 5 is a section taken on the line 5—5 of Fig. 4;

Fig. 6 is a section taken on the line 6—6 of Fig. 3;

Fig. 7 is a side elevation of a tufting clip formed from a single piece of metal; and

Fig. 8 is a section through one end of a clip showing another arrangement of clip and tack.

Referring to my invention as illustrated by the annexed drawing, I have shown, rather generally, a seat cushion structure which includes a spring unit including the usual coil springs 1 positioned between, and supported by, a frame 2 located

underneath the coil springs, and another frame 2^a on top of the springs and the structure also including the upholstered covering supported by the upper frame 2^a having the padding 3, the top covering material 4, and the bottom covering

4^a, all as shown in Fig. 1. Between the padding 3 and the top frame member 2^a is disposed a layer of extra padding 19, which prevents the thinner portions of the top padding 3 from coming in contact with the upper frame member. Here-

tofore the covering has been tufted by using tufting buttons exposed at the upper face of the covering and secured in position in various ways. I have found that a very neat appearing covering structure can be made by eliminating the exposed

45 tufting buttons. To accomplish my desired result I provide the covering 4 with folds and secure to each fold 5 (Figs. 1 and 2) one or more tufting devices 6 which are connected by ties 7 (Fig. 1) to a suitable anchoring means such, for instance,

50 as the wire 8 secured by hog-rings 9 to the frame structure adjacent to the bottom of the spring unit.

The particular tufting device which I have selected for illustration of my invention is in the

55 form of a clip which may be secured in position

by a rivet or tack which, if desirable, may be formed as an integral part of the clip, as shown in Fig. 7, or may be a separate member, as shown in Figs. 3 through 6, inclusive.

The particular clip which I have found to work 5 very satisfactorily is formed from sheet metal and the fold-engaging portion is bent into a substantially U-shaped form having side portions 11 and 12 (Figs. 3 and 5). The attaching member for the unit is in the form of a hollow tack substantially like that illustrated and described in United States Letters Patent to Gustav Johnson No. 1,931,728, issued October 24, 1933, and has a base 13 and a sharp pointed hollow shank 14. The attaching tack has a pair of ears 15—15 10 cut from the base and wrapped about the side 12 of the clip 10 in such a manner that the sharp pointed shank passes through an aperture 16 in the side 12 and extends toward the other side 11. The side 11 is also provided with an aperture 17 15 through which the shank 14 of the tack may pass when the clip is attached to the seat upholstery.

To attach my improved tufting clip, it is merely necessary to enter the fold 5 into the clip between the side 11 and the end of the tack 14 and then 20 squeeze the sides 11 and 12 toward each other thereby forcing the tack through the material of the fold 5 and through the aperture 17 in the side 11 of the clip 10. Thereafter the sharp pointed end of the shank 14 is upset or riveted 25 against the side 11 to hold the clip securely in position, as shown in Fig. 2. The clips are attached before the upholstery covering is placed in position upon the spring unit and the tie members 7, of leather, cords, coil springs, or the like, and 30 which are made up before attachment, are hooked into the loops provided at the bottom of the clips. These ties pass through apertures 18 in the upper part of the frame structure when the upholstery is placed in position and the other end of each 35 tie is anchored by pushing the wire 8 through the loop of each tie. The ends of the tie members are previously secured together by suitable clip members 19, as shown in Figure 1. These ties maintain a tension on the folds thereby keeping 40 the tufted appearance due to the fact that the ties are so arranged that the springs are always held under some compression.

In Figure 8 I have shown a portion of that end of a clip carrying the tack. Instead of the tack 50 being integral, as shown in Fig. 7, or held in place by ears, as shown in Fig. 6, it is secured in place merely by friction as the shank of the tack makes a driving fit with the wall surrounding the aperture in the arm of the clip.

While I have illustrated and described preferred embodiments of my invention, I do not wish to be limited thereby, because the scope of my invention is best defined by the following 5 claims.

I claim:

1. A seat cushion structure including a pair of spaced frame structures and spring means positioned between said frame structures, a padded cushion member on one of said frame structures, a covering for said member having a fold, a tufting device secured to said fold and being in the form of a U-shaped sheet metal clip having an attaching portion extending from one side thereof, said attaching portion being in the form of a sharp pointed tack extending through the fold at a point below the ends of said clip and through a hole in the other side and having its end portion upset and tie means connecting the clip to the lower of said frame structures to hold the fold under tension.
2. A tufting device of the class described formed from sheet metal and comprising a portion bent into substantially U shape, a tack having a base resting against one side of one of the sides of the U-shaped portion and having integral attaching portions engaged with the said side to secure the tack in position, and said tack having a hollow sharp pointed end extending from said base toward the other side.
3. A seat cushion structure including a pair of spaced frame structures and spring means positioned between said frame structures, a covering for said cushion having a downwardly extending fold, a U-shaped sheet metal tufting device having a leg extending upwardly at each side of said fold, said legs cooperating to grip the fold between them from the free ends of said legs to a point on each leg substantially below the free ends for the purpose of drawing opposite sides of said fold toward each other, a rigid attaching member extending from one leg of said tufting device at a point below the free end thereof through said fold and through the other leg to secure the device to the fold, said attaching member being completely concealed by the drawn-in sides of said fold and tie means connecting the

tufting device to a spaced frame structure to hold the fold under tension.

4. A tufting device of the class described comprising a member of substantially U-shaped cross-section having opposed sides connected by a loop at one end, said portion adapted to be bent only at said loop whereby said opposed sides may be moved toward one another, a rigid attaching member extending from one side of the U at a point spaced from the free end of that side toward the other side, and said other side having an aperture therethrough opposite the attaching member and spaced from the free end of said other side at a distance equal to that between the attaching member and the free end of said first side, said aperture adapted to receive said attaching member when the device is attached to a cushion structure.

5. A tufting device of the class described comprising a member of substantially U-shaped cross-section having opposed sides connected by a loop at one end, said portion adapted to be bent only at said loop whereby said opposed sides may be moved toward one another, a rivet extending from one side of the U at a point spaced from the free end of that side toward the other side, and said other side having an aperture therethrough spaced from the free end of said other side at a distance equal to that between the attaching member and the free end of said first side, said rivet adapted to pass through said aperture and have its end portion upset when the device is attached to a cushion structure.

6. In a cushion construction, spaced frame structures, spring means positioned between said frame structures, a padded cushion member on the outside of one of said frame structures, said cushion member having a covering having a fold extending downwardly, a plurality of individual tufting devices secured to the fold of the covering and having spaced means bearing against opposite sides of said fold, means connecting said spaced bearing means, each of said tufting devices being completely concealed by the covering, and tie means connecting the tufting devices to the other frame structure to hold the fold under tension.

CHARLES L. HALL.
